UNITED STATES PATENT OFFICE

145,075

DESIGN FOR A DECK OF PLAYING CARDS

Bernard L. Goldwater, West Haven, Conn.

Application October 6, 1945, Serial No. 122,579

Term of patent 14 years

(Cl. D34—13)

To all whom it may concern:

Be it known that I, Bernard L. Goldwater, a citizen of the United States, residing in West Haven, in the county of New Haven and State of Connecticut, have invented a new, original, and ornamental Design for a Deck of Playing Cards, of which the following is a specification, reference being had to the accompanying drawing, forming part thereof, in which the figure shows a suit of thirteen cards and a joker embodying my new design.

It is understood that the drawing shows the usual thirteen cards of one of the suits—namely, clubs, of the ordinary deck of four suits, and the

joker. The rank of the cards in each suit is designated by the insignia of military rank, beginning with a five-star general for the ace and descending to a private first class for the deuce. It will be understood that the cards of the other three suits of the deck, namely, diamonds, spades and hearts, will be similarly arranged.

The design of the back of each of the cards is conventional.

I claim:

The ornamental design for a deck of playing cards, substantially as shown and described.

BERNARD L. GOLDWATER.
